UNITED STATES PATENT OFFICE

ISIDOR NEWMAN, OF NEW YORK, N. Y.

DISPENSING SPOUT FOR CANS

Application filed November 4, 1930. Serial No. 493,361.

My present invention is a pouring spout for cans which are sealed with a so-called bung in a well known manner, such for example as is disclosed in my former Patents No. 1,266,519, issued May 14, 1918 and No. 1,370,040, issued March 1, 1921.

In dispensing the contents of cans sealed as above it is the common practice to pierce two or more holes in the top at separated 10 points, one for a vent and the other for pouring purposes. These apertures remain open and dust collects at and about them, frequently not only soiling the top of the can but contaminating the contents of the same. 15 Cans of the character used for containing such liquids as salad oil are usually provided with an upstanding rim or flange around the top. With such cans a portion of the poured contents of the can is usually dammed by the 20 said flange and when the can is set down the liquid seeks its own level and flows over a part or all of the top surface.

Further, there is nothing to direct the oil poured from such cans to the place of delivery and consequently there is frequently a loss, by slopping over, of some of the oil. 25

Since for convenience of packing it is desirable that the cans fit close together and that the tiers of cans rest flat one upon the 30 other, any form of pouring nozzle which extends beyond the flange and above the height of the flange that surrounds the top of the can is an undesirable adjunct to the can as a permanent fixture, since such nozzles would 35 interfere with the close packing of the cans.

Further, in providing the can with a pouring nozzle it is desirable that the nozzle need not itself be handled in order to effect the dispensing of the can; many nozzles which 40 have heretofore been proposed for use on cans require that their spouts be handled when oily material is upon the same in order to open and close the vent and pouring apertures, the spout constituting, as it were, the handle of a valve. This is objectionable for 45 obvious reasons and it is one of the objects of my invention to provide a nozzle free from these defects or deficiencies.

50 Another object is to provide a detachable

pouring nozzle which can be shipped separately from the cans and which may be used with as many cans as desired.

Further, it is an object to provide such a pouring spout or nozzle as will fit the ordinary can,—i. e., one which will require no changes in the can structure or that of its bung. 55

Further, it is an object to provide a pouring nozzle or spout of a simple and inexpensive nature that can be easily and cheaply manufactured and will effectively serve its intended purposes. 60

Further, it is an object to provide a nozzle with a convenient finger operable disk valve 65 by means of which, without changing the position of the spout with respect to the can, a stream of fluid or fluid in drops may be poured from the can with equal facility.

Other objects will in part be obvious and 70 in part be pointed out hereinafter.

To the attainment of the aforesaid objects and ends, the invention still further resides in the novel details of construction, combination and arrangement of parts, all of which 75 will be first fully described in the following detailed description, then be particularly pointed out in the appended claims, reference being had to the accompanying drawings, in which:— 80

Figure 1 is a perspective view of a portion of a can with my invention applied.

Figure 2 is an enlarged vertical longitudinal section of the same, the valve being closed.

Figure 3 is a view similar to Figure 2 with 85 the valve open.

Figure 4 is an inverted plan of the spout.

Figure 5 is a detail section on the line 5—5 of Figure 4.

Figure 6 is a detail top plan of the valve. 90

In the drawings in which like numerals of reference indicate like parts in all of the figures, 1 represents the can whose top 2 is provided with a mouth 3 surrounded by an upstanding flange 4. After the can has been 95 filled the mouth is closed by means of a cup-like bung 5 having a skirt 6 to fit over the flange 4 and be secured thereto by such means as are disclosed in my previous patents above referred to. 100

The bung 5 is preferably provided with a weakened or scored part to provide a removable section 8 which can be knocked in when it is ready to dispense the contents of the can see Figures 2 and 3.

My invention comprises the spout 10 which has a cup-like portion 11 designed to snugly fit within the bung 5. The spout is also provided with an annular flange or skirt 12 that 10 overlies the bung skirt 6 and the flange or skirt 12 is provided with resilient prongs or nibs 13, at suitable intervals, (preferably three arranged in triangular formation) which provides resilient means for holding 15 the spout cup in and to the bung with retaining friction, the resiliency of the prongs 13 tending to cause pressure against the bung skirt.

The spout cup 11 is provided with a vent 20 hole 14 and a pouring hole 15 which are covered by a valve disk 16 riveted to the spout cup as at 17, the valve disk having corresponding vent and pouring holes designed when the valve disk is in one position to 25 register with those of the spout cup, and when the valve is in another position to be out of register with the same whereby the valve disk will close the holes in the spout cup.

The valve disk has a handle portion 19 30 which extends out of the cup over the rim of the spout cup and terminates in a finger piece 18 having side flanges 20 as shown.

In using my invention the removable section 8 is punched out (or if there be no removable section provided, then two diametrically opposite holes, one for pouring and one for venting, may be punched out with a sharp instrument) then the spout cup 11 is pressed over the bung until it snaps into place where 40 it is held with friction enough to retain it and yet allow it to be swivelled in order that the spout may be directed where desired for pouring purposes. After placing the spout where desired, then the pouring of the contents is controlled wholly by the disk valve 16. By turning the valve to bring its apertures more or less into register with the spout cup, either a full stream or fluid may be poured from the can, or the fluid may be dispensed in drops since the adjustment of the areas of the openings may be made very fine.

After the can is empty the spout may be pried off and used on another can. In this way one spout may be made to serve for the dispensing of the contents of any number of cans desired.

From the foregoing description, taken in connection with the accompanying drawings, 50 it is thought the construction, operation and advantages of my invention will be clear, and I desire it understood that changes in the details of construction and design of parts may be made without departing from the invention as defined in the appended claims.

What I claim is:

1. In combination with a can having a mouth with an upstanding flange and a cup-like bung secured in said mouth and having a skirt overlying said flange, said bung adapted to have a section removed to provide a pouring opening; a spout comprising a pouring spout proper and a spout cup, the latter fitting into said bung and having a skirt overlying the skirt of the bung, means holding said spout cup in place with retaining friction, said spout cup having a pouring hole, and a disk valve swivelly secured to and in said spout cup and having a pouring hole to register with that of said spout cup when said disk valve is one position. 70

2. In combination with a can having a mouth with an upstanding flange and a cup-like bung secured in said mouth and having a skirt overlying said flange, said bung adapted to have a section removed to provide a pouring opening; a spout comprising a pouring spout proper and a spout cup, the latter fitting into said bung and having a skirt overlying that of the bung, spring nibs on the skirt of the spout cup for holding said spout cup in place with retaining friction, said spout cup having a pouring hole, and a disk valve swivelly secured to and in said spout cup and having a pouring hole to register with that of the spout cup when said disk valve is turned into one position, said disk valve having a handle finger piece projecting upwardly over the top of said spout cup. 80

3. In combination with can having a mouth with an upstanding flange and a cup-like bung secured to said mouth and having a skirt overlying said flange, said bung adapted to have a section removed to provide a pouring opening; a spout comprising a pouring spout proper and a spout cup, the latter fitting within said bung and having a skirt overlying the skirt of the bung, means holding said spout cup in place with retaining friction, said spout cup having a pouring hole and a vent hole, and a disk valve swivelly secured to and in said spout cup over said holes and itself having a pouring hole and a vent hole adapted to be brought into register with the corresponding holes of the spout cup when said disk valve is in one position, and a handle finger piece carried by said valve by which it may be turned. 1

4. A can having a mouth with an upstanding flange and a cup-like bung secured in said mouth and having a flange overlying the rim of the upstanding flange of the cup mouth, said bung adapted to have a section removed to provide a pouring opening, combined with a pouring spout removably secured to said bung and including a cup member having a flange overlying the flange of the bung and provided with nibs to engage the flange of the bung for retaining the cup member removably in the bung. 1

5. A can having a mouth with an upstanding flange and a cup-like bung secured in said mouth, said bung adapted to have a section removed to provide a pouring opening, combined with a pouring spout removably secured to said bung, said pouring spout comprising a spout proper and a spout cup, the latter fitting into said bung, and means holding said spout cup removably in place with 10 retaining friction, said spout cup having a pouring hole, and a disk valve swivelly secured to and in said spout cup and having a pouring hole to register with that of said spout cup when said disk valve is in one position.
